UNITED STATES PATENT OFFICE

JAMES EDWIN DAVIS, OF GLEN COVE, NEW YORK

DESIGN FOR A TOY DOG TEAM AND SLED

Application filed August 13, 1930. Serial No. 36,653. Term of patent 3½ years.

To all whom it may concern:

Be it known that I, JAMES E. DAVIS, a citizen of the United States, residing at Glen Cove, Long Island, in the county of Nassau and State of New York, have invented a new, original, and ornamental Design for a Toy Dog Team and Sled, of which the following is a specification, reference being had to the accompanying drawing, forming part thereof.

I claim:

The ornamental design for a toy dog team and sled, as shown.

JAMES EDWIN DAVIS
